BOTTLE

John F. Watson, Chatham, N. J.

Application January 16, 1951, Serial No. 13,815

Term of patent 14 years

(Cl. D58—6)

To all whom it may concern:

Be it known that I, John F. Watson, a citizen of the United States, residing at Chatham, in the county of Morris and State of New Jersey, have invented a new, original, and ornamental Design for a Bottle, of which the following is a specification, reference being had to the accompanying drawings, forming a part thereof.

Figure 1 is an elevational view of a bottle, showing my new design, the design having the same appearance when viewed from the opposite side;

Figure 2 is an elevational view of the bottle turned 90° about its vertical axis, the design having the same appearance when viewed from the opposite side;

Figure 3 is a top plan view;

Figure 4 is a sectional view taken along the line 4—4 of Figure 1.

I claim:

The ornamental design for a bottle, as shown and described.

JOHN F. WATSON.
